LUBRICATING APPARATUS

Carl H. Mueller, Pasadena Hills, Mo., assignor to The McNeil Machine & Engineering Company, Akron, Ohio, a corporation of Ohio

Application December 21, 1956, Serial No. 629,928

3 Claims. (Cl. 222—376)

This invention relates to lubricating apparatus, and more particularly to hand-operated grease guns.

Among the several objects of the invention may be noted the provision of an improved hand-operated grease gun, and more particularly a lever-type gun, adapted for short-stroke operation in confined quarters, as well as for full-stroke operation, and the provision of such a grease gun which is economical to manufacture and reliable in operation for various grades of grease. Other objects and features will be in part apparent and in part pointed out hereinafter.

The invention accordingly comprises the constructions hereinafter described, the scope of the invention being indicated in the following claims.

In the accompanying drawings, in which one of various possible embodiments of the invention is illustrated,

Fig. 1 is a view partly in side elevation and partly in longitudinal cross section of a grease gun of this invention;

Fig. 2 is an enlarged section taken on line 2—2 of Fig. 1; and,

Fig. 3 is an enlarged fragment of Fig. 1 illustrating a moved position of parts.

Corresponding reference characters indicate corresponding parts throughout the several views of the drawings.

Referring to the drawings, a grease gun of this invention is shown to comprise a container or barrel 1 for containing a supply of grease. At one end of the barrel 1 is a pump generally designated P. This pump comprises a head 3 screwed on the end of the barrel and having a bore 5 extending transversely with respect to the barrel. This bore constitutes the pump cylinder. A pump plunger 7 reciprocates in the bore or cylinder 5. The plunger extends out of one end of the cylinder 5 (the rearward end of the cylinder). A hand lever 9 is pin-connected at 11 adjacent one end to the end of the plunger which extends out of the cylinder. A link 13 is pin-connected at 15 to this end of the lever and pin-connected at 17 to the head 3. The arrangement is such that by swinging the lever away from the barrel 1, the plunger 7 is pulled out through a priming or return stroke, and by swinging the lever toward the barrel, the plunger is pushed in through a pressure stroke.

The head 3 is formed with a main lateral inlet port 19 for the cylinder 5 through which grease may flow from the barrel 1 into the cylinder 5 when the plunger 7 is fully retracted through a full return stroke. In the barrel is a follower 21 biased toward the head 3 by a spring 23 for forcing grease from the barrel into the cylinder. The forward end of the cylinder 5 is closed by a plug 25. The head is formed with a lateral outlet port 27 adjacent the forward end of the cylinder. Screwed in the outlet port 27 is an outlet pipe 29. On the outer end of the pipe is a conventional hydraulic coupler 31.

The forward end portion of the cylinder 5 is enlarged as indicated at 33 to provide a forwardly facing valve seat 35 inward of the outlet port 27. A valve ball 37 is

2

biased toward this seat by a spring 39 reacting from the plug 25. The head P is formed with an auxiliary lateral inlet port 41 for the cylinder 5 inward of and closely adjacent the valve seat 35 through which grease may flow from the barrel 1 into the cylinder 5 when the plunger 7 is retracted through a short stroke. The auxiliary port 41, as shown best in Fig. 2, is drilled at an angle intersecting the cylinder 5 at one side. The port 41 is counter-bored to form an outwardly facing valve seat 43 located between the barrel end of the port and the cylinder 5. A valve ball 45 is inserted in the port 41 from its outer end for engagement with the seat 43 under pressure from the cylinder 5 to block off flow of grease from the cylinder back into the barrel through port 41. A conventional filler nipple 47 is threaded in the outer end of port 41 and closes it. A spring 49 is interposed between the inner end of the nipple 47 and a shoulder 51 formed in the port 41.

Operation is as follows:

On a full return stroke of the plunger 7, the plunger is withdrawn to the left as viewed in Figs. 1 and 3 beyond the main inlet port 19 for priming of the cylinder 5 with grease from the barrel 1. Some grease may enter the cylinder via the ball-checked auxiliary inlet port 41, but priming occurs mainly via the wide-open main inlet port 19 to insure full and rapid priming, even in the case of heavy grease. Then, on a pressure stroke of the plunger, the inlet port 41 is closed by the valve ball 45 to prevent return of grease to the barrel via port 41, valve ball 37 opens, and the charge of grease in the cylinder is delivered through the outlet port 27.

In the case the gun needs to be used in confined quarters where it is not possible to take a full stroke of the lever 9 and the plunger 7, a short return stroke of the plunger to the point where port 41 is open to the cylinder 5 (see Fig. 3) will prime the cylinder via port 41. Then, on a pressure stroke of the plunger, the ball 45 closes and the charge of grease (in this case a small charge) is delivered through the outlet port 27.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. Lubricating apparatus comprising a lubricant container and a pump, the pump comprising a body having a bore therein constituting a pump cylinder and a plunger slideable in the bore, said body having a main inlet intersecting the bore adjacent one end of the bore which constitutes the rearward end of the bore and an auxiliary inlet intersecting the bore between the main inlet and the other and forward end of the bore for flow of lubricant from the container to the bore, said plunger being slideable in the bore between a fully retracted position wherein the forward end of the plunger is rearward of at least part of the main inlet and a forward position wherein its forward end is forward of the auxiliary inlet, said body having an outlet in communication with the forward end of the bore, a check valve in the outlet adapted to open in response to lubricant pressure developed on a forward stroke of the plunger and to close on a return stroke of the plunger, a valve seat in the auxiliary inlet facing in the direction of flow toward the bore, and an auxiliary check valve in the auxiliary inlet engageable with said valve seat, said auxiliary check valve being constantly free to move away from said valve seat to open on a return stroke of the plunger and adapted in response to lubricant pressure developed in the bore on a

forward stroke of the plunger to seal against said valve seat and block off flow from the bore back to the container through the auxiliary inlet, whereby the plunger is adapted either for full-stroke operation or for short-stroke operation involving retraction thereof from its forward position to an intermediate position wherein its forward end is rearward of at least part of the auxiliary inlet and forward of the main inlet.

2. A grease gun comprising a barrel for containing grease, a head at one end of the barrel having a bore therein constituting a pump cylinder, a plunger slidable in the bore, a lever carried by the head for moving the plunger, the head having a main inlet intersecting the bore adjacent one end of the bore which constitutes the rearward end of the bore and an auxiliary inlet intersecting the bore between the main inlet and the other and forward end of the bore for flow of grease from the barrel to the bore, said plunger being slidable in the bore between a fully retracted position wherein the forward end of the plunger is rearward of at least part of the main inlet and a forward position wherein its forward end is forward of the auxiliary inlet, said head having an outlet at the forward end of the bore including a portion of larger cross section than the bore and being formed so that there is a forwardly facing annular valve seat surrounding the forward end of the bore, a spring-biased outlet check valve engageable with said forwardly facing valve seat adapted to open in response to grease pressure developed

in the bore on a forward stroke of the plunger, a valve seat in the auxiliary inlet facing in the direction of flow toward the bore, and a check valve in the auxiliary inlet engageable with said valve seat in the auxiliary inlet, said 5 check valve for the auxiliary inlet being constantly free to move away from the valve seat in the auxiliary inlet to open on a return stroke of the plunger and adapted in response to grease pressure developed in the bore on a forward stroke of the plunger to seal against said auxiliary inlet valve seat and block off flow from the bore back to the barrel through the auxiliary inlet, whereby the plunger is adapted either for full-stroke operation or for short-stroke operation involving retraction thereof from its forward position to an intermediate position wherein its forward end is rearward of at least part of the auxiliary inlet and forward of the main inlet.

10 15 20 25 3. A grease gun as set forth in claim 2 wherein the auxiliary inlet is constituted by a passage extending completely through the head and intersecting the bore, said passage being formed adjacent its end toward the barrel with said auxiliary inlet valve seat, the outer end of the passage being closed by a filler nipple.
